PRESSURE ACTUATED FUEL INJECTION
SYSTEM FOR FREE-PISTON ENGINESRalph J. Hooker, Hamilton, Ohio, assignor to
United Aircraft Corporation, East Hartford,
Conn., a corporation of Delaware

Application June 10, 1947, Serial No. 753,642

13 Claims. (Cl. 123—46)

1
This invention relates to a pressure actuated fuel injection system particularly adapted for free-piston units.

In compression ignition engines, it is advantageous in many cases to have the fuel injected at a predetermined compression pressure. This has been accomplished by arranging the fuel injection device so that the flow of fuel into the engine cylinder will take place under the control of a valve which is responsive to pressure within the engine cylinder. A feature of this invention is the actuation of the pump plunger by pressure from the engine cylinder. Another feature is the arrangement of the device, such that the injection plunger is moved rapidly on the injection stroke when the predetermined compression pressure is reached.

Free-piston units generally have air springs which function to move the engine pistons on the compression stroke. These air springs may be a part of the compressor elements or may be separate air springs. In either event the air pressure in the air spring is highest at the end of the power stroke of the engine piston at which time the pressure in the engine cylinder is at a minimum. A feature of this invention is the use of pressure as from the air spring for returning the injection plunger on the filling stroke. It will be understood that instead of air spring pressure, the pressure within the compressor cylinder might be used.

A feature of the invention is an arrangement for adjusting the quantity of fuel for each stroke of the plunger by limiting the plunger stroke.

Other objects and advantages will be apparent from the specification and claims and from the accompanying drawings which illustrate an embodiment of the invention.

Fig. 1 is a sectional view of the free-piston unit showing the injection pump in elevation.

Fig. 2 is a sectional view on a larger scale of the injection device.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assembly. The sleeves in conjunction with stationary pistons 28 and 30 form air spring cylinders.

The pistons are moved apart by the burning of fuel injected into engine cylinder 10 through a fuel nozzle 32, Fig. 2. Air compressed in the air spring cylinders on the power stroke returns the piston assemblies on the compression stroke.

2
The pistons are always maintained at equal distances from the center of the engine cylinder by a linkage, not shown.

The intake manifold 38 which extends around the compressor and engine cylinders conducts air to intake valves 40 in the heads of the compressor cylinders through which air automatically enters the opposite ends of the cylinders. Compressed air leaves the cylinders through discharge valves 42, also at opposite ends of the compressor cylinders and passes into a central scavenging chamber 44 and end chambers 46 and 48. These chambers may be connected by a scavenging manifold, not shown.

Compressed air from the scavenging chambers enters engine ports 50 which are uncovered by piston 14 at the end of the power stroke, thereby permitting air to be blown through the engine cylinder. Gas in the engine cylinder is discharged through exhaust ports 52 uncovered by the piston 12 and into an exhaust manifold 54.

The fuel for the nozzle 32 is supplied by a fuel injection device which is actuated on the injection stroke by a compression pressure and which is returned on the pumping stroke by air from one of the air springs. As shown in Fig. 2, the injection device includes a casing 56 having a fuel inlet 58. Within the casing is a cylinder 60 having a bore in which the injection plunger 62 reciprocates. The cylinder has an inlet passage 64, the inner end of which is covered by the plunger on the injection stroke, thereby trapping fuel in the end of the bore 66 and forcing it out past a check valve 68 and through the nozzle 32. The latter may be held in place by a ring 70 which also functions to hold the cylinder 60 in position.

The plunger extends beyond the cylinder 60 at its outer end and engages with a disc 72 which is moved outwardly by a spring 74, thereby holding the end of the plunger against the rod 76 of a piston 78. The piston 78 is slideable in a casing 80 and has a projecting valve element 82 which closes an inlet passage 84 in the casing which is connected, as by a pipe 86, with the engine cylinder. When the pressure in passage 84 is high enough to overcome the action of the spring 74, the piston 78 moves upwardly, allowing the compression pressure from the engine cylinder to be effective over the entire area of the piston and cause rapid upward movement of the piston and corresponding movement of the injection plunger to deliver fuel to the engine cylinder.

The other side of the piston 78 is acted upon

by pressure from one of the air springs through a duct 88 and a passage 90 in a plate 32 between the outer end of the casing 56 and the end of the casing 80. As the pistons reach the outer ends of their strokes so that the engine cylinder pressure drops to that of the pressure in the scavenging manifolds, the air spring pressure will be high enough to return the piston 78 to the position shown, thereby causing the injection plunger to return to the position shown under the action of the spring 74.

For limiting the quantity of fuel injected on each stroke, the casing 56 supports a ring 94 having teeth 95 on its outer surface engageable with a rack 96 slidable in the casing. The inner surface of the ring 94 has splines 98 engaging with the outer surface of a sleeve 100 which has threads cooperating with similar threads 102 on the cylinder 60. Movement of the rack 96, one end of which extends beyond the casing 56, thus turns the sleeve 100 on the cylinder and adjusts the vertical position of the lower end of the sleeve, thereby limiting the plunger stroke since the disc 72 engages with the end of the sleeve.

For the purpose of adjusting the time of injection, the tension of spring 74 may be changed as by substituting a different spring. An alternative adjustment may be effected by providing a ring 102 in the casing 56 surrounding and in threaded engagement with the periphery of the plate 104 against which the spring 74 rests. When the ring 102 is turned as by a rack 106 engaging teeth 108 on the ring, the plate 104 will be moved downwardly to increase the tension of the spring. A pin 110 may hold the plate against turning. Obviously the actuation of rack 106 may be manual or automatic, as desired.

In operation, with the parts in the position shown, the engine pistons are moved toward each other to build up a pressure in the engine cylinder for the purpose of igniting the fuel to be injected therein. When this compression pressure reaches a predetermined value, which is a function of the area of the passage 84, and the strength of spring 74, the piston 78 is moved rapidly upward, thereby moving the plunger 62 upwardly, first closing the inlet passage 64 and then forcing fuel past the check valve and through the fuel nozzle into the engine cylinder. This causes combustion to take place in the engine cylinder, and the pistons move apart, thereby building up a pressure in the air springs. When the exhaust ports are uncovered causing a substantial drop in the pressure in the engine cylinder, air spring pressure is acting on the upper side of the piston 78 returning it to the position shown, thereby causing the return of the injection plunger to the position shown so that the space 66 may again be filled with fuel in readiness for the next injection.

It is to be understood that the invention is not limited to the specific embodiment herein illustrated and described, but may be used in other ways without departure from its spirit as defined by the following claims.

I claim:

1. A free-piston unit including opposed piston assemblies including engine and compressor pistons, an engine cylinder in which the engine pistons are positioned, compressor cylinders at the ends of the engine cylinder for the compressor pistons, and air springs acting on each piston assembly for moving the assemblies toward each other on the compression stroke, in combination

with an injection device for delivering fuel to the engine cylinder, said device including a housing having a bore and an inlet port to said bore, a plunger reciprocating in said bore, and a nozzle through which fuel entering said inlet is delivered to the engine cylinder, and means responsive to pressure in the engine cylinder for moving the plunger on the injection stroke.

2. A free-piston unit including opposed piston assemblies including engine and compressor pistons, an engine cylinder in which the engine pistons are positioned, compressor cylinders at the ends of the engine cylinder for the compressor pistons, and air springs acting on each piston assembly for moving the assemblies toward each other on the compression stroke, in combination with an injection device for delivering fuel to the engine cylinder, said device including a housing having a bore and an inlet port to said bore, a plunger reciprocating in said bore, and a nozzle through which fuel entering said inlet is delivered to the engine cylinder, means responsive to pressure in the engine cylinder for moving the plunger on the injection stroke, and other means for causing the plunger to move in the opposite direction on the filling stroke in response to pressure in the air spring.

3. A free-piston unit including opposed piston assemblies including engine and compressor pistons, an engine cylinder in which the engine pistons are positioned, compressor cylinders at the ends of the engine cylinder for the compressor pistons, and air springs acting on each piston assembly for moving the assemblies toward each other on the compression stroke, in combination with an injection device for delivering fuel to the engine cylinder, said device including a housing having a bore and an inlet port to said bore, a plunger reciprocating in said bore, and a nozzle through which fuel entering said inlet is delivered to the engine cylinder, means responsive to pressure in the engine cylinder for moving the plunger on the injection stroke, and other means for causing the plunger to move in the opposite direction on the filling stroke in response to pressure in the air spring.

4. A free-piston unit including opposed piston assemblies including engine and compressor pistons, an engine cylinder in which the engine pistons are positioned, compressor cylinders at the ends of the engine cylinder for the compressor pistons, and air springs acting on each piston assembly for moving the assemblies toward each other on the compression stroke, in combination with an injection device for delivering fuel to the engine cylinder, said device including a housing having a bore and an inlet port to said bore, a plunger reciprocating in said bore, and a nozzle through which fuel entering said inlet is delivered to the engine cylinder, means responsive to pressure in the engine cylinder for moving the plunger on the injection stroke, and means for limiting the stroke of the plunger for controlling the fuel quantity delivered on each stroke.

5. A free-piston unit including an engine cylinder and piston, a compressor cylinder and piston, said cylinders being connected together and said pistons being interconnected to reciprocate as a unit in said cylinders, an air spring including piston and cylinder elements, one of which is connected to the pistons to move therewith, said air spring causing movement of the pistons on the engine compression stroke, in combination with an

injection device for delivering fuel to the engine cylinder including a fuel injection pump, means for actuating the pump for the delivery of fuel to the engine cylinder in response to pressure in the engine cylinder, and means for causing the pump to move on the filling stroke in response to pressure in the air spring.

6. A free-piston unit including an engine cylinder and piston, a compressor cylinder and piston, said cylinders being connected together and said pistons being interconnected to reciprocate as a unit in said cylinders, an air spring including piston and cylinder elements, one of which is connected to the pistons to move therewith, said air spring causing movement of the pistons on the engine compression stroke, in combination with a fuel injection device for delivering fuel to the engine cylinder including a housing having a bore and an injection plunger reciprocating in said bore, a passage from said bore to the engine cylinder and an inlet passage for fuel to enter said bore, a spring acting on said plunger to move it in one direction, and pressure-actuated means for moving the plunger in the opposite direction, said pressure-actuated means being connected to the engine cylinder.

7. A free-piston unit including an engine cylinder and piston, a compressor cylinder and piston, said cylinders being connected together and said pistons being interconnected to reciprocate as a unit in said cylinders, an air spring including piston and cylinder elements, one of which is connected to the pistons to move therewith, said air spring causing movement of the pistons on the engine compression stroke, in combination with a fuel injection device for delivering fuel to the engine cylinder including a housing having a bore and an injection plunger reciprocating in said bore, a passage from said bore to the engine cylinder and an inlet passage for fuel to enter said bore, a spring acting on said plunger to move it in one direction, and pressure-actuated means for moving the plunger in the opposite direction, said last means including a piston, a cylinder in which said piston reciprocates, and a valve element substantially smaller in area than the piston connected thereto, said valve element closing an admission port to the last-mentioned cylinder.

3. A free-piston unit including an engine cylinder and piston, a compressor cylinder and piston, said cylinders being connected together and said pistons being interconnected to reciprocate as a unit in said cylinders, an air spring including piston and cylinder elements, one of which is connected to the pistons to move therewith, said air spring causing movement of the pistons on the engine compression stroke, in combination with a fuel injection device for delivering fuel to the engine cylinder including a housing having a bore and an injection plunger reciprocating in said bore, a passage from said bore to the engine cylinder and an inlet passage for fuel to enter said bore, a spring acting on said plunger to move it in one direction, and pressure-actuated means for moving the plunger in the opposite direction, said last means including a piston, a cylinder in which said piston reciprocates, and a valve element substantially smaller in area than the piston connected thereto, said valve element closing an admission port to the last-mentioned cylinder, said admission port communicating with the engine cylinder.

9. A free-piston unit including an engine cylinder and piston, a compressor cylinder and piston, said cylinders being connected together and said

pistons being interconnected to reciprocate as a unit in said cylinders, an air spring including piston and cylinder elements, one of which is connected to the pistons to move therewith, said air spring causing movement of the pistons on the engine compression stroke, in combination with a fuel injection device for delivering fuel to the engine cylinder including a housing having a bore and an injection plunger reciprocating in said bore, a passage from said bore to the engine cylinder and an inlet passage for fuel to enter said bore, a spring acting on said plunger to move it in one direction, and pressure-actuated means for moving the plunger in the opposite direction, said pressure-actuated means being connected to the engine cylinder, said pressure-actuated means including a piston and a cylinder in which the piston reciprocates, said piston being connected to the plunger, and a connection from one side of said piston to the engine cylinder.

10. A free-piston unit including an engine cylinder and piston, a compressor cylinder and piston, said cylinders being connected together and said pistons being interconnected to reciprocate as a unit in said cylinders, an air spring including piston and cylinder elements, one of which is connected to the pistons to move therewith, said air spring causing movement of the pistons on the engine compression stroke, in combination with a fuel injection device for delivering fuel to the engine cylinder including a housing having a bore and an injection plunger reciprocating in said bore, a passage from said bore to the engine cylinder and an inlet passage for fuel to enter said bore, a spring acting on said plunger to move it in one direction, and pressure-actuated means for moving the plunger in the opposite direction, said pressure-actuated means being connected to the engine cylinder, said pressure-actuated means including a piston and a cylinder in which the piston reciprocates, said piston being connected to the plunger, a connection from one side of said piston to the engine cylinder, and a connection from the other side of said piston to the air spring.

45 11. A free-piston unit including an engine cylinder and piston, a compressor cylinder and piston, said cylinders being connected together and said pistons being interconnected to reciprocate as a unit in said cylinders, an air spring including piston and cylinder elements, one of which is connected to the pistons to move therewith, said air spring causing movement of the pistons on the engine compression stroke, in combination with a fuel injection device for delivering fuel to the engine cylinder including a housing having a bore and an injection plunger reciprocating in said bore, a passage from said bore to the engine cylinder and an inlet passage for fuel to enter said bore, a spring acting on said plunger to move it in one direction, and pressure-actuated means for moving the plunger in the opposite direction, said pressure-actuated means being connected to the engine cylinder, said pressure-actuated means including a piston and a cylinder in which the piston reciprocates, said piston being connected to the plunger, and a connection from one side of said piston to the air spring.

12. A free-piston unit including an engine cylinder and piston, a compressor cylinder and piston, said cylinders being connected together and said pistons being interconnected to reciprocate as a unit in said cylinders, an air spring including piston and cylinder elements, one of which is connected to the pistons to move therewith, said air spring causing movement of the pistons on

the engine compression stroke, in combination with a fuel injection device for delivering fuel to the engine cylinder including a housing having a bore and an injection plunger reciprocating in said bore, a passage from said bore to the engine cylinder and an inlet passage for fuel to enter said bore, a spring acting on said plunger to move it in one direction, and pressure-actuated means for moving the plunger in the opposite direction, said last means including a piston, a cylinder in which said piston reciprocates, and a valve element substantially smaller in area than the piston connected thereto, said valve element closing an admission port to the last-mentioned cylinder, said spring normally holding the valve element in closed position, and thereby controlling the engine cylinder pressure at which the injection of fuel occurs.

13. A free-piston unit including an engine cylinder and piston, a compressor cylinder and piston, said cylinders being connected together and said pistons being interconnected to reciprocate as a unit in said cylinders, an air spring including piston and cylinder elements, one of which is connected to the pistons to move therewith, said air spring causing movement of the pistons on the engine compression stroke, in combination with a fuel injection device for delivering fuel to the engine cylinder including a housing having a bore and an injection plunger reciprocating in

said bore, a passage from said bore to the engine cylinder and an inlet passage for fuel to enter said bore, a spring acting on said plunger to move it in one direction and pressure-actuated means for moving the plunger in the opposite direction, said last means including a piston, a cylinder in which said piston reciprocates, and a valve element substantially smaller in area than the piston connected thereto, said valve element closing an admission port to the last-mentioned cylinder, said spring normally holding the valve element in closed position, and thereby controlling the engine cylinder pressure at which the injection of fuel occurs, and means for adjusting the tension of said spring for adjusting the pressure required for causing the injection of fuel.
